UNITED STATES PATENT OFFICE.

LEO J. GRUBMAN, OF NEW YORK, N. Y., ASSIGNOR, BY MESNE ASSIGNMENTS, TO VOICES, INCORPORATED, OF NEWARK, NEW JERSEY, A CORPORATION OF DELAWARE.

ARTICULATIVE SOUND-PRODUCING DEVICE FOR DOLLS, ETC.

Application filed December 20, 1922. Serial No. 607,931.

To all whom it may concern:

Be it known that I, LEO J. GRUBMAN, a citizen of the United States, and a resident of the borough of Bronx, county of 5 Bronx, city and State of New York, have invented certain new and useful Improvements in Articulative Sound-Producing Devices for Dolls, Etc., of which the following is a specification sufficient to enable those 10 conversant with the art to which the invention appertains to utilize the same.

My improvements relate to the type of sound-producing devices designated primarily for incorporation in toys, and especially dolls, etc., in which the production of articulatory syllabical sounds in imitation of the human voice is the object to be attained, substantially in the manner set forth in my concurrent applications for 15 patents on the same subject, Serial No. 542,884, filed March 11th, 1922, and Serial No. 601,725, filed November 16th, 1922. As in both of the said concurrent applications, the main object of my present invention is the 20 production of simple, substantial, compact, "self-contained" mechanism of the character designated, which is gravity-automatic in operation in that the use of springs is obviated, as well as the necessity for external 25 pressure for sound production, the specific object of this invention being the variation, regulation, and perfection of the syllabized expression, and the facilitation of operation. To this end the invention 30 consists in the specific combination, arrangement and construction of parts and appurtenances herein described and claimed—distinctive features being the means provided for modifying sound emission, and for 35 avoiding retardant inflation of the air compression chamber, all as hereinafter fully set forth.

I herein exemplify in the accompanying drawings a practical and preferred embodiment of the essential features of my invention, without, however, limiting myself to the identical form and construction of parts shown, because changes may be made in minor details with the attainment of like 40 results, and without departing from the spirit and intent of my invention in this respect.

With this understanding,

Fig. 1, shows a side elevation of my articulative sound producing device; 55

Fig. 2, an elevation of the intersticed end thereof; and

Fig. 3, an elevation of the closed end thereof;

Fig. 4, is a central vertical sectional elevation taken upon plane of line 4—4, Fig. 3, illustrating the position of the parts when the air compression chamber is inflated; 60

Fig. 5, is a central vertical sectional elevation taken upon plane of line 5—5, Fig. 2, 65 showing the position of the parts just prior to the collapse of the air compression chamber;

Fig. 6, is a view of the inner side of the movable head of the compression chamber; 70

Fig. 7, is an elevation of the outer face of the movable head of the compression chamber;

Fig. 8, is a central section of said movable head of the compression chamber, 75 taken upon plane of line 8—8, Fig. 7;

Fig. 9, is a view like unto Fig. 5, showing the compression chamber fully collapsed;

Fig. 10, is an external elevation, on an 80 enlarged scale, of the nasal aperture throttle valve;

Fig. 11, is a central longitudinal section thereof;

Fig. 12, is a transverse section taken upon 85 plane of 12—12, showing the nasal aperture open;

Fig. 13, is a like view showing the nasal aperture, closed;

Fig. 14, is a diagrammatic view illustrating 90 the position of the sounding device as related to the doll body in which it is enclosed.

The operative parts of my sound producing device are, as heretofore, enclosed in a 95 rigid casing, consisting, in the preferred form shown herein, of a cylindrical shell *c*, closed at one each of what is designated for convenience of description as the basic disc *c'*, and at the other extremity by an intersticed head plate or disc *c''*, although the external configuration of the casing is of 100 secondary importance, its function being simply to isolate and protect said operative

parts, and to afford fixed external dimensions, in such manner as to render the device, considered in a unitary sense, self-contained, and without protuberant parts other than the head of the nasal throttle valve as hereinafter set forth. Thus it is obvious that the shell or casing c , c' , c^2 , might be other than cylindrical in shape extraneous with substantially like results, although the form shown herein is preferable, on account of its simplicity, compactness, and cheapness of structure.

The head plate c^2 , of the casing is intersticed, or formed with one or more apertures c^3 , for communication with the atmosphere, but such apertures c^3 , may be formed elsewhere in the casing, if desired. As shown herein, a series of these air ports or perforations c^3 , are located in the head plate c^2 , of the casing as indicated more particular in Figs. 2, 4, 5 and 9, of the drawings, provision thus being made for the free inlet and outlet of air, and the emission of sound vibrations emanating from the interior of the device, as hereinafter set forth.

The wind chest or sound emission pipe a , which also functions as a guide and lateral support for the free or movable head b , of the bellows B , which, in this construction, constitutes the air compression chamber, is likewise preferably, but not necessarily, of cylindrical form, and positioned centrally as related to said bellows and the casing, it being fixedly secured to and between the base plate c' , and the head plate c^2 , as shown more particularly in Figs. 4, 5, and 9, of the drawings. Thus, it may consist of a tube a , held in place at one extremity by being seated in a depression c'' , in the base plate c' , and at the other extremity by the inner medial edge c^{22} , of the head plate c^2 , fitting in an annular groove a' , (Figs. 4, 5, 9, 10, and 11) formed for the purpose in the peripheral surface of said wind pipe a , adjacent to the end thereof, the extreme outer edge of the tube being peaned or bent over the outer surface of said head plate c^2 , thereby locking the said wind pipe a , securely in place.

This extremity of the throat or wind pipe a , is closed by the nasal valve N , the hollow cylindrical portion n , of which extends into the wind pipe a , as shown more particularly in Figs. 9 and 11, of the drawings, fitting snugly therein so as to make an air tight joint therewith. The other extremity of said wind pipe a , is closed and held in position by the aforesaid depression c'' , in the basic disc c' .

Within, and adjacent to this end of the wind pipe a , is positioned a reed r , or equivalent sound producing element, the side of the tube in proximity thereto, and between it and the inner side of the basic disc c' , being formed with one or more apertures as a^x , through which communication is estab-

lished with the interior of the bellows B , so as to afford adequate means for the admission of air to, and its expulsion from, the air compression chamber of said bellows B , according to circumstances, as for instance for the inflation or deflation of said bellows B , always effected through said wind pipe a .

Air is admitted to or ejected from the wind chest a , through the medium of the primary or nasal aperture a^2 , and the secondary or aspirate aperture a^3 , both of which communicate under certain conditions, with the space c^x , between the intersticed head plate c^2 , of the casing and the resonator or sound intensifying partition P , which latter is rigidly positioned within the casing and is related to said head plate c^2 , as shown more particularly in Figs. 4, 5 and 9, of the drawings.

Said resonance partition P , is preferably of concave form on the side thereof opposed to the intersticed head plate c^2 , of the casing, as shown in the drawings, so as to concentrate and align the sound waves or vibrations emanating from the wind chest a , in a manner essentially parabolic, although I do not limit myself in this respect, since the main function of said partition P , is to definitely limit the sound productive area of the device and separate it from the rest of the interior of the casing, it having been found that otherwise the collapse of the bellows B , causes the movable head b , thereof to attenuate the sound vibrations by enlarging the area between it and the perforated head c^2 thus interfering materially with and modifying the sound production in such manner that the second syllable produced is less distinct than the first.

The said resonator partition P , is formed with a central opening p , for the accommodation of the wind chest a , and it may be affixed to the casing in any suitable manner, preferably by the method set forth in my last named concurrent application Serial No. 601,725, which also describes the means herein shown for effecting the permanent attachment of other portions of the device, said details of construction forming no part of my present invention.

In this connection it may be stated that the improvements herein sought to be covered relate especially to the means for controlling the intake and outlet of air to and from the device in such manner that complete inflation of the air compression chamber is assured, and also whereby the device may be adjusted to pronounce syllabically either the words "pa-pa" or "ma-ma", as desired.

It is to be understood that the difference in the pronunciation of these two words consists, in the case of ma-ma, in the production of a preliminary nasal sound before

vowel "A"; whereas the absence of such preliminary nasal sound results in the articulation of the syllabical sound "pa-pa". The usual method heretofore followed in sound devices simulating the word "ma-ma" has been to produce a sound inside a chamber otherwise closed except for two sound-emitting openings, one of which (the first or preliminary opening as related syllabical 5 pronunciation) is smaller than the other, and has been constantly open, even though the larger opening be closed temporarily. Thus the nasal sound of the letter "M" is first heard emitted through the smaller opening 10 before the larger opening is uncovered by its co-operating valve, and then at the moment the larger opening uncovered the vowel "A" follows the consonant "M" thereby producing the syllable "ma". The omission of the 15 smaller opening results in the pronunciation of the syllable "pa".

A distinctive feature of my present invention consists in the provision of means whereby the smaller or preliminary nasal 20 opening a^2 , may be closed or opened at will, so that a doll equipped with my improved "voice" device may be set to ejaculate either "papa" or "mama", as desired, by the simple expedient of turning the nasal valve N, in 25 one direction or the other.

It is obvious that various well known mechanical expedients may be resorted to for thus covering or uncovering the nasal opening a^2 , and I do not limit myself to the form 30 of valve disclosed herein which, however, is well adapted to the purpose in that it is simple in structure, and also functions as a closure for this extremity of the throat pipe a. As shown in the accompanying drawings, 35 said valve consists of a hollow cylindrical stem portion n, extending into the throat tube a, beyond the nasal aperture a^2 , thereof, and formed with an opening n', corresponding to said nasal opening a^2 , and which may 40 be brought into coincidence therewith, as illustrated in Fig. 12, or out of coincidence therewith, as in Fig. 13, of the drawings, the extent of rotative movement of the valve in either direction being limited by a boss 45 or projection a^3 , inturned on the throat tube a, and protruding into a segmental slot n², formed for the purpose in said cylindrical portion n, of the valve N, as shown more 50 particularly in Figs. 11, 12 and 13 of the drawings, by reference to which it will be seen that the ends of the slot n², when contacting with the boss a^3 , of the tube a, act as stops to limit movement of the valve in either direction. Incidentally the protrusion 55 of the boss a^3 , into the transverse segmental slot n², prevents the slipping out or removal of the said cylindrical portion n, of the valve N, from the throat tube a, thereby securing 60 said valve N, in position.

The outer end of the cylindrical portion n,

of the valve N, is formed with prongs n³, n⁴, which project through the disk of the "button" n⁴, which latter constitutes the handle or finger piece by means of which the valve N, may be manipulated,—said "button" 70 n⁴, being intended to protrude through the back of the doll D, as indicated in Fig. 14, and to be utilized and disguised as a possible fastening for a part of the doll clothing, 75 said Fig. 14, also showing in dotted lines the preferred position of the "voice" device within the body of the doll.

In order to prevent possibility of leakage of air through the disc n⁴, around the prongs n³, n⁴, I insert a sealing plug n⁵, in the outer 80 extremity of the cylindrical portion n, of the nasal valve N, as shown more particularly in Figs. 9 and 11, of the drawings.

An important requirement to insure perfect operation of a device of this character where a bellows B, is used as the air compression chamber, is the complete inflation of said bellows before the start of the retractile, or compressive movement of its weighted movable head b, otherwise the latter may move a considerable portion of its collapsion stroke without perceptibly compressing the air in the bellows, causing partial or complete failure in the pronunciation of the first syllable or its consonant, and resulting in the sounds "ama" or "apa", or only the last syllable of either word. Or, to indicate the trouble in different language, the imperfect inflation of the bellows may cause the completion of the expansion stroke of the weighted head b, to create a partial vacuum or tension within the bellows that has to be overcome before actual compression of air is attained, thus impairing initiative sound 95 production as above stated.

I obviate this difficulty, in my construction of apparatus herein set forth, by providing the movable head b, of the bellows B, with one or more auxiliary air inlet openings b', b², the first, b', being positioned to coincide with the throat opening a^3 , when the said movable head b, is at the completion of its expansion stroke, as in Fig. 4, of the drawings, so as to insure an adequate supply of intake air through the throat pipe a; or an inlet port b³, may be made in the said movable head b, communicating directly with the interior of the bellows B, when said inlet port b³, is uncovered by the automatic opening of its closure flap b⁴, as 100 also shown in said Fig. 4, of the drawings, Fig. 9, of the latter showing said flap b⁴, as closed by internal pressure during the compression stroke of the movable head b. 105 It is to be noted that in both instances the air inlets b', b², are valve controlled in that the neck of the movable head b, in one case acts as the valve to open and close the aperture a^3 , in the throat tube a, and in this 110 respect being the equivalent of the flap valve 115

b^1 , provided for the direct port b^2 . The latter, it is to be noted, insures an ingress of air to the bellows B, even after the inlet a^3 , in the throat tube a, is closed by the 5 neck of the movable member, and up to and during the completion of the expansive stroke of said movable head of the bellows, so that all tendency of rarefaction of air within the bellows is obviated in a positive 10 manner, the valve b^2 , closing automatically at the inception of the retractile or collapse-stroke of the movable head b .

What I claim as my invention and desire to secure by Letters Patent is,

15 1. In an articulating device, an air chamber, a gravity movable air expelling member in said chamber, a sound producing reed through which the air is expelled, relatively fixed means with which said member 20 coacts to control the emission of sound simulating the pronunciation of vowel letters and additional means adapted to cooperate with said fixed means for independently controlling the emission of sound in 25 relatively different volume from that normally emitted through said first-named means for simulating the pronunciation of consonant letters.

30 2. In an articulating device, an air chamber, a member movable in said chamber for expelling air therefrom, a sound producing reed through which the air is expelled, a relatively fixed part guiding said member and having means with which said member 35 coacts to control the emission of sound simulating the pronunciation of vowel letters, said part also having additional sound emitting means, and a manually operable element adapted to cooperate with said last-named sound emitting means for independently controlling the emission of sound therefrom in relatively different volume 40 from that emitted through said first-named means for simulating the pronunciation of consonant letters.

45 3. In an articulating device an air compression chamber, a wind chest communicating therewith and with the atmosphere, said wind chest being formed with a preliminary nasal throat aperture of relatively small area and with a second throat aperture of larger size, means for opening and closing said preliminary nasal throat aperture in the wind chest, consisting of a rotative valve having a cylindrical stem portion fitting in the end of the wind chest and formed with a port for coincidence with said nasal throat aperture in said wind chest, 50 means for limiting the rotative movement of said valve, a sound producing element positioned in said wind chest, and means for inflating and deflating said air compression chamber.

60 4. In an articulating device, a casing, having an air receiving chamber therein,

sound producing and emitting means including a fixed part extending axially through said casing and having spaced sound emission openings of relatively different size, a member movable upon said part for expelling air from said chamber through the sound producing means and said member having means to coact with one of said openings and control the emission of sound therethrough, and means accessible from the exterior of said casing for opening or closing communication between the other of said emission openings and the atmosphere to thereby independently control the emission of sound through the latter opening. 70 80

5. In an articulating device, sound producing and emitting means including a fixed tubular part having spaced sound emission openings of relatively different area, a bellows provided with a gravity movable head 85 guided by said tubular part and adapted to expel air through the sound producing means, said head being provided with a part to intermittently interrupt the emission of sound from one of said openings, and means 90 independently operable from the exterior of said tubular part to open or close the other of said sound emission openings and thereby independently control the emission of sound through said latter opening. 95

6. In a sound producing device, a cylindrical air chamber, a gravity movable air expelling member in said chamber, sound producing and emitting means including a tubular part extending axially through said chamber and having spaced openings in its wall of relatively different area, said expelling member coacting with the latter opening in said tubular part to control the emission of sound therethrough, and a manually 100 adjustable valve member associated with said tubular part and adapted to open or close the smaller opening thereof to independently control the emission of sound 105 therethrough. 110

7. In an articulating device, a casing having an air receiving chamber therein, sound producing and emitting means including a tubular member positioned axially through said casing and opening at one of its ends through one end of said casing, said member being provided in its wall with longitudinally spaced sound emission openings, a movable member in said casing for expelling air from said chamber through the sound producing and emitting means, and a manually adjustable valve element mounted in the open end of said tubular member for the purpose of opening or closing one of said sound emission openings to thereby optionally control the character of the emitted sounds. 115 120 125

8. In an articulating device, a casing having heads on its opposite ends and an air receiving chamber enclosed within said cas- 130

ing, sound producing means, a gravity movable member in the casing expelling air from said chamber through the sound producing means, and means mounted between

5 and supported by the casing heads for controlling the emission of the sounds including relatively adjustable parts for the purpose of simulating the sounding of either one of two different words during the air 10 expelling movement of said member.

9. In a sound producing device, a cylindrical casing, sound producing means within said casing, means for expelling air under pressure from said casing through the sound 15 producing means, and sound emission controlling means positioned in the major axial line of said casing and including a manually adjustable part optionally operable to vary the volume and audible impression of 20 the emitted sound.

10. In a sound producing device, a cylindrical casing, sound producing means within said casing, means for expelling air under pressure from said casing through the sound 25 producing means, and sound emission controlling means positioned in the major axial line of said casing and including an axially rotatable part optionally operable to vary the volume and audible impression of the 30 emitted sound.

11. In an articulative sound producing device, a casing, an air chamber enclosed thereby, a member longitudinally movable in the casing for expelling air from said 35 chamber, a sound producing reed through which the air is expelled, and normal emission means and optional emission means coaxially related to said movable air expelling member for optionally effecting the emission 40 of sound in phonetic simulation of different word syllables.

12. In an articulative sound producing device, a casing, a bellows enclosed within said casing having a longitudinally movable head 45 for expelling air from the bellows chamber, a sound producing reed through which the air is expelled, and sound emission controlling means positioned in the line of axial movement of said bellows head and including an emission and a rotatably-adjustable part coacting with said opening and optionally operable to effect the emission of sound in phonetic simulation of different word 50 syllables.

55 13. In an articulative sound producing device, a casing, an air chamber enclosed thereby, a member longitudinally movable in the casing for expelling air from said chamber, a sound producing reed through 60 which the air is expelled, manually controllable means coaxially related to said movable air expelling member for optionally effecting the emission of sound in phonetic simulation of different word syllables, said means including an orificed guide element

for said expelling member, a sound emission control element coacting with one of the orifices of said guide element, and means for adjusting one of said elements with respect to the other to thereby optionally 70 effect the emission of sound in phonetic simulation of different word syllables.

14. In an articulative sound producing device, a casing, a bellows enclosed within said casing having a longitudinally movable head for expelling air from the bellows chamber, a sound producing reed through which the air is expelled, and sound emission controlling means positioned in the line of axial movement of said bellows head, 75 said means including an orificed guide member for said movable bellows head, a sound emission control member associated with said guide member, and means for rotatably adjusting one of said members with respect 80 to the other to control the emission of sound through the orifices of said guide and thereby effect the phonetic simulation of different word syllables.

15. In an articulating device, a casing, an air receiving chamber enclosed by said casing, sound producing means, a gravity movable member in the casing for expelling air from said chamber through the sound producing means, and means for controlling the emission of the sound including a sound receiving chamber positioned axially of said casing and having spaced sound emission openings in its wall, said air expelling member having means to co-operate with one of said openings and control the emission of sound therethrough, and manually adjustable means accessible from the exterior of the casing to open or close the other sound emission opening and thereby 90 independently control the emission of sound 95 through the latter opening.

16. In an articulating device, a bellows having a gravity movable head, a fixed 100 guide for the movable bellows head having a passage communicating at one of its ends with the interior of the bellows and provided with spaced emission openings at its other end communicating with the atmosphere, sound producing means through which air is expelled by the bellows into said passage, means carried by the movable bellows head for controlling the emission of sound through one of said openings in 105 its air expelling movement upon said guide, and separate means for independently controlling the emission of sound through the other of said openings.

17. In an articulating device, a casing, an air receiving chamber enclosed by said casing, a fixed guide member extending axially through the casing and said chamber, a gravity movable air expelling member supported and guided by said member, 110 said member having a passage therethrough 115

- communicating at one of its ends with said chamber and communicating at longitudinally spaced points near its opposite end with the atmosphere, sound producing means through which air is expelled from said chamber into said passage, means carried by said gravity movable member for controlling the emission of sound through one of the latter openings in the air expelling movement of said member, and adjustable means associated with said member for independently controlling the emission of sound through the other of said openings.
18. In a sound producing device, a bellows having a gravity movable head, a fixed guide for said head having a sound emission and air admitting passage therethrough communicating at one of its ends with the interior of the bellows and at its other end with the atmosphere, sound producing means through which the air is expelled in the deflation movement of the bellows head, said bellows head having an apertured part controlling the emission of sound through said passage, and the aperture thereof being adapted to register with the outlet of said passage at the end of the reverse movement of said bellows head whereby the interior of the bellows is in communication with the atmosphere to thereby effect the complete inflation of the bellows chamber.

LEO J. GRUBMAN.
